UNITED STATES PATENT OFFICE.

EDWARD J. BULLOCK, OF WALLINGFORD, CONNECTICUT, ASSIGNOR OF ONE-HALF TO MERWIN D. TUTTLE, OF SAME PLACE.

INSULATOR-PIN.

SPECIFICATION forming part of Letters Patent No. 527,318, dated October 9, 1894.

Application filed February 9, 1894. Serial No. 499,656. (No model.)

To all whom it may concern:

Be it known that I, EDWARD J. BULLOCK, of Wallingford, in the county of New Haven and State of Connecticut, have invented a new 5 Improvement in Insulator-Pins; and I do hereby declare the following, when taken in connection with accompanying drawings and the letters of reference marked thereon, to be a full, clear, and exact description of the same, 10 and which said drawings constitute part of this specification, and represent, in—

Figure 1, a view in side elevation of an insulator-pin constructed in accordance with my invention; Fig. 2, a view thereof in vertical longitudinal section; Fig. 3, a view of the pin in transverse section on the line $y-y$ of Fig. 2.

My invention relates to an improvement in insulator-pins which are used in the cross-bars of the poles or masts used for running telegraph, telephone and other electric wires. Heretofore these pins, which are made of wood, have been found objectionable because under exposure to the weather, they decay, 25 and break off, and so foul the wires, which are restored to place with difficulty on account of their elevated location.

With these ends in view, my invention consists in an insulator-pin having certain 30 tails of construction as will be hereinafter described and pointed out in the claim.

As herein shown, the pin, which has a long tapering head A, and a cylindrical stem A' slightly smaller in diameter than the head, is 35 constructed with a central longitudinal bore A², entering it from the outer end of its head, and extending considerably below the longitudinal center of its stem. In this head I locate a reinforce, consisting as shown, of a 40 metal tube D, which is shorter in length than the length of the bore, so that when it is driven home, the outer end of the bore will

be left unoccupied for the reception of a plug C, which is made of wood, and corresponds in diameter to the diameter of the bore, in which 45 it is secured by glue or cement, or some equivalent material, so as to seal the bore up with a reinforce in it. If desired, the reinforce may consist simply of a solid rod, but a tubular reinforce is lighter and quite as strong. 50 After the bore has been formed in the pin, I preferably treat the pin with some wood preserving composition, rendering it less liable to decay, the bore forming a conduit as it were, and enabling the wood to be much more 55 thoroughly impregnated than if the preserving fluid were applied only to its outer surface.

An insulator-pin constructed in accordance with my invention is stronger than pins as 60 heretofore constructed, less liable to decay, and if in the course of time the wood does decay and break away, the metal reinforce remains to maintain the wires in place until the pin can be replaced.

Having fully described my invention, what I claim as new, and desire to secure by Letters Patent, is—

An insulator-pin for electric wires, having a long longitudinal bore formed in it, a metal 70 reinforce located within the said bore but shorter than the length of the same, and a plug fitted tightly into the open end of the bore over the outer end of the reinforce, and sealing the same within the pin, substantially 75 as and for the purpose described.

In testimony whereof I have signed this specification in the presence of two subscribing witnesses.

EDWARD J. BULLOCK.
